UNITED STATES PATENT OFFICE

AARON SHATKIN, OF BROOKLYN, NEW YORK

METHOD OF MAKING SHEET METALWARE JOINTS

Application filed May 27, 1930. Serial No. 456,070.

The present invention relates to the joining of sheet metal shells or forms which make up the component parts of candle-sticks, salt shakers, fruit bowls, vases and similar class 5 of articles. These articles are usually made up of spun or stamped shells or forms which are soldered together. One of the objects of this invention, is to dispense with the soldering operations which are costly and 10 require skill, and to provide a joint construction which will join the several parts of these articles in a simple, inexpensive and secure manner. Another object of my invention is to provide a joint which will not allow the 15 joined parts from becoming dis-associated even by abuse. To these and other ends, this invention consists in the novel method and construction hereinafter described, illustrated and claimed.

20 In the accompanying drawing, forming a part of this application, similar characters of reference indicate corresponding parts in all the views.

Fig. 1 is a view partly in elevation and 25 partly in section of a candlestick showing an embodiment of my invention.

Fig. 2 is a similar view showing another embodiment thereof.

Fig. 3 is a similar view of a salt shaker 30 showing another embodiment of my invention.

Fig. 4 is a fragmentary view of one of the shells or forms to be joined, showing the partially corrugated or crimped contact surface.

35 Fig. 5 is an enlarged sectional view of the joint.

Fig. 6 is an enlarged sectional view of the joint as adapted to water-tight compartments construction.

40 Fig. 7 is a view partly in elevation and partly in section of a vase showing embodiments of my invention.

Fig. 8 is a view partly in elevation and 45 partly in section of a candlestick which is made up of many parts, showing another embodiment of my invention.

I carry out this invention by corrugating or crimping corresponding portions of the contact surfaces of the shells or forms to be joined, passing an eyelet through all of said

shells or forms through perforations therefor provided, arranging the several parts to be joined, so that the corrugated surfaces engage or mesh, and then by closing the eyelet to hold all the parts securely together. The eyelet will be either long or short, depending upon the number of parts to be joined together. The eyelet prevents the several shells or forms from becoming dis-associated, while the contact surfaces being engaged or meshed, none of the several parts so joined can be turned about the eyelet independently. 55

Referring to the drawing, candle socket holder 16 and base 12 have their contact surfaces corrugated or crimped with corrugations 25, and both parts of the candlestick shown in Fig. 1, are joined by an eyelet 10 passed through perforations 9'. Washers 9 are provided as shown, to give greater rigidity to the joint. Fig. 5 is an enlarged view 70 of this joint.

The separate eyelet may be dispensed with, by fashioning one of the parts to be joined to include an equivalent of the eyelet as is shown in the candle-stick of Fig. 2. The candle socket holder 16' has a nipple 11 extending downward from its bottom, and said nipple 11 serves as an eyelet. Flange 11' is formed by an eyelet closing or setting instrument. 75

In the construction of salt shakers, the compartment 17 used for holding salt must be salt tight; and in vases the compartment 12' must be water tight. The joint shown in Fig. 5 would be adaptable for such purposes 80 should the hole 26 of the eyelet 10 be closed. I therefor cover the eyelet 10 with a cap 18, and the water tight joint is shown in enlarged section in Fig. 6. Washers 9 are provided to give the joint greater rigidity. When the joint is made as shown in Fig. 5, the washer 9 and the flange 10' of eyelet 10, protrude 85 above the surface of the bottom of candle socket holder 16. In order to make a flush surface, the joined parts 16 and 12 should be provided and formed with depressed cups 27 and 28, as are the joined parts 13 and 17 shown in the enlarged view in Fig. 6. 90

The components 12' and 16'' of the liquid-holding compartment of the case shown in 100

Fig. 7, are joined together by a joint similar to the construction shown in Fig. 5.

In the construction of candlesticks or other standards made up of many parts of the type shown in Fig. 8, all of the component parts 5 may be securely joined by a long eyelet 19. All contact surfaces of candle socket holder 20 and part 21, parts 21 and 22, parts 22 and 23, parts 23 and 24, and of part 24 and base 10 15, are each crimped with corrugations 25, and are meshed. Eyelet 19 prevents the component parts of the candle-stick from becoming dis-associated, and the meshing of the corrugated portions of the contact surfaces 15 of the several component parts prevents any of the parts of the standard from being able to be turned about the eyelet independently.

The articles of the class herein mentioned, constructed according to the present invention, 20 have considerably greater strength against destruction than the same articles having soldered joints. The cost of manufacture of these articles are reduced by employing the method herein described, and no 25 skilled labor is required in the assembling operations.

I claim:

1. The method of joining any number of sheet-metal shells or forms, which consists in 30 perforating each of the parts to be joined, corrugating corresponding portions of all contact surfaces, so that one part can engage or mesh with the other part with which it is to be in contact, passing an eyelet through the 35 perforations, arranging the parts so that the corrugations engage or mesh, and closing the eyelet.

2. The method of joining any number of shells or forms made of sheet material, which 40 consists in perforating each of the parts to be joined, corrugating corresponding portions of all contact surfaces, so that one part can engage or mesh with the other part with which it is in contact, passing a fastening 45 means through the said perforations, arranging the parts so that the corrugations engage or mesh, and securing the fastening means.

In testimony whereof, I have hereunto set my hand.
